THREAD GUIDE SUPPORT IN SPINNING MACHINES

Walter Hoffmann, Zurich, Switzerland, assignor to Actiengesellschaft Joh. Jacob Rieter & Cie., Winterthur, Switzerland, a corporation of Switzerland

Application April 28, 1950, Serial No. 158,664
In Switzerland May 2, 1949

9 Claims. (Cl. 57—110)

1

The present invention relates to a carrier mechanism for the thread guides in spinning machines.

An object of the present invention is the provision of a carrying mechanism for the thread guides on spinning machines which means can be actuated for simultaneous change of the elevational position of all thread guides. The mechanism comprises a bar extending below the drawing-roll frames and has uprights at its ends which are guided in vertical grooves in support bars for the drawing-roll frames. The thread guides are mounted on a horizontal rod supported by the uprights. Guides for the thread guide carrier according to the invention can be easily manufactured and supervised, and the carrier moves in such guides practically without friction. Slow upward movement of the thread guide carrier prevents movements which interfere with the equalization of the thread tension during spinning.

The carrier according to the invention is preferably suspended by flexible members, such as chains, which extend over rolls which are supported by walls or framework arranged in the main frame of the spinning machine.

The flexible members suspending one carrier are preferably connected to a common bar pulling on the members when moved in axial direction. A chain or other flexible member is connected with one end of the bar and extends in line with the bar to a roll arranged at one end of the spinning machine for being wound on said roll when the machine is in operation. The winding rolls for the last mentioned chains for raising (and lowering) the carriers of one machine are preferably fixed to a common shaft which is driven by another shaft by means of a third flexible means. This third means or one of the shafts is provided with a weight or resilient means for counterbalancing the weight of the thread guide carriers and for reducing the power needed for raising the carriers.

A further object of the invention is the provision of adjusting means for simultaneous adjustment of the initial elevational position of all thread guides of a spinning machine. The adjusting means comprise a sleeve rotatably and axially movably connected with the actuating shaft for a mechanism for changing the elevational position of the thread guides. The sleeve has a slanted end surface cooperating with a radial pin on said shaft. Upon axial movement of the sleeve relative to the shaft, the slanted end surface which engages the pin causes rota-

2

tion of the shaft and thereby adjustment of the initial position of the thread guides relative to the position of the shaft.

Further and other objects of the present invention will be hereinafter set forth in the accompanying specification and claims, and are shown in the drawings which, by way of illustration, show what I now consider to be preferred embodiments of the invention.

10 In the drawing:

Fig. 1 is a schematic, fractional side elevation, partly in section, of a spinning machine equipped with the mechanism according to the invention and omitting the parts not pertinent to the invention;

Fig. 2 is a cross-sectional, schematic, fractional view of the spinning machine as shown in Fig. 1, the scale of Fig. 2 being larger than that of Fig. 1;

Fig. 3 is a schematic, large scale view of a portion of the mechanism shown in Fig. 1 looking outward on Fig. 1;

Fig. 4 is a perspective view showing the drive of the device according to the invention by a conventional mechanism.

Like parts are designated by like numerals in all figures of the drawing.

Referring more particularly to the drawing, numeral 2 designates rods extending along the sides of the spinning machine and supporting thread guides 1 of which a few only are shown in Fig. 1. Rods 2 are supported by upright portions at the ends of carrier members 3 whose horizontal portions are placed below angle irons 4, which support the drawing-roll frames, which are not shown as they do not form part of the present invention. Members 3 are provided with vertical grooves 5 serving as guides for the upright portions of carrier members 3 which slide freely in said grooves. Carriers 3 are suspended at both sides of the spinning machine by chains 6 which extend over rollers 7 borne in intermediate frames or walls 8. The chains 6 at each end of a carrier are connected to a common bar

9, there being two bars for each carrier. One end of a chain 10 is connected to the end of each bar on the driving end of the machine, the other ends of chains 10 being individually made fast on rollers 11. Rollers 11 are connected with a transverse shaft 12 to which is fixed a drive roller 13. One end of a chain 14 is connected with roller 13 and its other end is connected to a roller 15 placed below roller 13. A weight 16 is connected with chain 14 between rollers 13 and 15.

Numerals 17 designates the spindle carrier.

Upon counterclockwise rotation of shaft 12, as viewed in Fig. 1, chains 10 are wound on rollers 11 and bars 9 are pulled to the left and pull on chains 6 thereby raising carriers 3. This causes simultaneous raising of all thread guides 1 on both sides of the machine. At the same time chain 14 is wound on roller 15 and unwound from roller 13. Weight 16 counterbalances the weight of carriers 3 and parts connected thereto and facilitates movement thereof. The weight of carriers 3 and parts connected therewith causes a moment of rotation on shaft 12 through bars 9 and chains 10 which is somewhat smaller than that effected by the weight 16 through chain 14. Thus the chain 14 is tensioned even when running on roller 15. If, for example, roller 15 rotates clockwise, chain 14 unwinds from said roller and is wound at the same time on roller 13 due to the weight of the carriers 3 which are thereby permitted to descend.

For adjusting the initial position of all carriers 3, a mechanism may be provided as illustrated in Fig. 3. In this case, drive roller 13 is fixed to a sleeve 21 in which shaft 12 is rotatable and axially slidably. Sleeve 21 and shaft 12 are rotatably and at least the last axially slidably carried in supports 18. One end of sleeve 21 has a slanted face 20 on which slides a pin 19 extending radially from shaft 12. The end of shaft 12 which is borne in sleeve 21 is provided with a threaded extension 12' projecting from sleeve 21. By tightening nut 22 on extension 12', shaft 12 is moved to the left as seen in Fig. 3 and into sleeve 21 causing pin 19 to ride up on surface 20, thereby rotating shaft 12 in a direction to pull on chains 10 for raising carriers 3. The mechanism provides for simultaneous adjustment of the initial elevation of all thread guides 1.

The roller 15 is preferably operated by the builder mechanism which is provided in conventional spinning machines for actuating the ring rail. Such a mechanism is diagrammatically illustrated in Fig. 4. It comprises a lever member 23 swinging on pin 25 and having a free end hung on the ring rail by a chain 24. A cam follower roller 26 supported on lever member 23 engages cam 27. The free end of member 23 carries a shaft 29 by means of brackets 28, which shaft carries a ratchet wheel 30 connected with a worm 31. Wheel 30 is engaged by a pawl 32 swinging about a stationary fulcrum. Worm 31 actuates a worm wheel 33 on a shaft 34 rotatably carried and disposed longitudinally of lever member 23. At one end of shaft 34 is a roller 35 to which chain 24 is connected and at the other end is the roller 15 to which the chain 14 is connected.

When the machine is in operation, cam 27 rotates clockwise and causes oscillating movement of member 23. Roller 35 is thereby moved up and down and actuates the ring rail through chain 24 in the conventional manner. Pawl 32 causes clockwise rotation of ratchet wheel 30 and worm 31 at each downward movement of the left end of member 23. At the same time worm wheel 33, shaft 34, and rollers 35 and 15 are rotated causing winding of chain 24 on the former and of chain 14 on the latter. Winding of chain 14 causes unwinding of said chain from roller 13 and counterclockwise rotation of shaft 12 and rollers 11 in Fig. 1 and winding of chains 10 on the latter, whereby carriers 3 are raised.

While I believe the above described embodiments of my invention to be preferred embodiments, I wish it to be understood that I do not desire to be limited to the exact details of method,

design and construction shown and described, for obvious modifications will occur to a person skilled in the art.

I claim:

5. In a spinning machine having two ends, a support means placed on each end of the machine, vertical guide means connected with said support means, a plurality of carrier members individually having a substantially horizontal portion extending transversely to and underneath said support means and having vertical end portions individually guided in said guide means for affording guided up and down motion of said carrier members, a support member connected with said vertical portions on each end of the machine, and thread guides supported by said support member.

2. In a spinning machine as defined in claim 1, intermediate frame means extending parallel to said carrier members and supporting said support means, rollers supported by said frame means, and flexible suspension means extending over and depending from said rollers and connected to and suspending said carrier members.

3. In a spinning machine as defined in claim 1, intermediate frame means extending parallel to said carrier members and supporting said support means, rollers supported by said frame means, flexible suspension means individually extending over and having an end depending from said rollers and connected to and suspending said carrier members, substantially horizontal rod members longitudinally movably supported in said frame means, the other ends of the flexible means being connected with said rod members for raising and lowering the suspended carrier members upon longitudinal movement of the rod members in one or the opposite direction, a flexible member connected with one end of each of said rod members, and rolls individually connected with said flexible members and adapted to wind and unwind said members for longitudinally moving the connected rod members and raising and lowering said carrier members.

4. In a spinning machine as defined in claim 1, intermediate frame means extending parallel to said carrier members and supporting said support means, rollers supported by said frame means, flexible suspension means individually extending over and having an end depending from said rollers and connected to and suspending said carrier members, substantially horizontal rod members longitudinally movably supported in said frame means, the other ends of the flexible means being connected with said rod members for raising and lowering the suspended carrier members upon longitudinal movement of the rod members in one or the opposite direction, a flexible member connected with one end of each of said rod members, a shaft placed transversely to the longitudinal axes of said rod members, rolls mounted on said shaft, said flexible members being individually connected with said rolls and adapted to be wound thereon and unwound therefrom for longitudinally moving the connected rod members and raising and lowering said carrier members, and means connected with said shaft for rotating it in the direction for winding said flexible members on said rolls and counterbalancing the unwinding force caused by the weight of said carrier members.

5. In a spinning machine as defined in claim 1, intermediate frame means extending parallel to said carrier members and supporting said support means, rollers supported by said frame

means, flexible suspension means individually extending over and having an end depending from said rollers and connected to and suspending said carrier members, substantially horizontal rod members longitudinally movably supported in said frame means, the other ends of the flexible means being connected with said rod members for raising and lowering the suspended carrier members upon longitudinal movement of the rod members in one or the opposite direction, a flexible member connected with one end of each of said rod members, a shaft placed transversely to the longitudinal axes of said rod members, rolls mounted on said shaft, said flexible members being individually connected with said rolls and adapted to be wound thereon and unwound therefrom for longitudinally moving the connected rod members and raising and lowering said carrier members, and drive means connected with said shaft for rotating it for raising said carrier members.

6. In a spinning machine as defined in claim 1, intermediate frame means extending parallel to said carrier members and supporting said support means, rollers supported by said frame means, flexible suspension means individually extending over and having an end depending from said rollers and connected to and suspending said carrier members, substantially horizontal rod members longitudinally movably supported in said frame means, the other ends of the flexible means being connected with said rod members for raising and lowering the suspended carrier members upon longitudinal movement of the rod members in one or the opposite direction, a flexible member connected with one end of each of said rod members, a shaft placed transversely to the longitudinal axes of said rod members, rolls mounted on said shaft, said flexible members being individually connected with said rolls and adapted to be wound thereon and unwound therefrom for longitudinally moving the connected rod members and raising and lowering said carrier members, and another flexible means extending around and connected with said shaft for rotating it, a weight suspended by said other flexible means for rotating the shaft in the direction for winding said flexible members on said rolls and counterbalancing the unwinding force caused by the weight of said carrier members.

7. A spinning machine comprising support means, substantially vertical guide means connected with said support means, a plurality of

carrier members individually having two end portions individually guided in said guide means for up and down movement of said carrier members, a support member connected with one of the end portions of said carrier members, a second support member connected with the other end portion of said carrier members, a plurality of thread guides connected with said support members, actuating means connected with said carrier members and comprising a shaft whose rotation in one direction effects upward movement of said carrier members and whose rotation in the opposite direction effects downward movement of said carrier members, drive means for said shaft, and adjusting means interposed between said shaft and said drive means for initially setting the position of said shaft relative to said drive means.

8. A spinning machine as set forth in claim 7, said adjusting means comprising a sleeve connected with said drive means, said shaft having an end portion extending into said sleeve and being rotatable and axially movable therein, a pin radially extending from said shaft, said sleeve having a guide surface slidably engaging said pin and being slanted with respect to the rotation axis of said sleeve, and means for changing the relative axial position of said shaft and of said sleeve for rotating said shaft relative to said sleeve by the engagement of the slanted surface and the pin.

9. A spinning machine as set forth in claim 7, said adjusting means comprising a sleeve connected with said drive means, said shaft having an end portion extending into said sleeve and being rotatable and axially movable therein, a pin radially extending from said shaft, said sleeve having a guide surface slidably engaging said pin and being slanted with respect to the rotation axis of said sleeve, said sleeve having an end surface at a right angle to its rotation axis, the end portion of said shaft being threaded and projecting beyond said end surface of said sleeve, and a nut screwed on said end portion and abutting said end surface and affording change of the relative axial position of said shaft and of said sleeve upon tightening of said nut and rotation of said shaft relative to said sleeve by the engagement of the slanted surface and the pin.

WALTER HOFFMANN.
